UNITED STATES PATENT OFFICE.

MAURICE B. LONG, OF EAST ORANGE, NEW JERSEY, ASSIGNOR TO WESTERN ELECTRIC COMPANY, INCORPORATED, OF NEW YORK, N. Y., A CORPORATION OF NEW YORK.

CARRIER TRANSMISSION SYSTEM.

Application filed March 31, 1923. Serial No. 629,007.

This invention relates to a carrier transmission system, and more particularly to a multiplex carrier telegraph system employing carrier currents of audio frequency. 5 Such a multiplex carrier telegraph system employing carrier currents of audio frequency may be utilized to advantage on long distance telephone lines. Long distance telephone lines, as designed for telephone use, 10 are highly efficient for the transmission of audio frequency currents. Therefore a carrier telegraph system employing audio frequency carrier currents may be applied to such a long distance telephone line without 15 changing in any wise the usual line equipment such as loading coils, amplifying repeaters, filters and other apparatus.

Such a multiplex audio frequency carrier telegraph system may be applied in similar 20 manner to a channel of an existing multiplex high frequency carrier or a multiplex radio telephone system.

Among the objects of the invention are: 25 To provide an efficient and economical multiplex carrier telegraph system operating with carrier currents of audio frequency.

To provide a multiplex carrier system wherein modulation between channels of 30 different systems operating with carrier currents of the same frequency from the same source and between adjacent channels of 35 the same system operating with carrier currents of different frequencies is so reduced as to be negligible.

To improve the quality of the transmitted 40 marking and spacing signals.

To provide a carrier telegraph system wherein the marking signals are unbiased.

To provide in a receiving channel of a 45 carrier current system a receiver which discriminates between signal currents and interfering line currents of smaller amplitude.

To provide a multiplex carrier telegraph system employing carrier currents of audio 50 frequency which may be applied efficiently and economically to a channel of a multiplex radio or a multiplex high frequency carrier telephone system.

In the drawings, 55 Fig. 1 shows diagrammatically the terminal apparatus and circuits of a multiplex audio frequency carrier telegraph system.

Fig. 2 shows a modulating circuit so organized as to improve the quality of the 60 transmitted signals.

Fig. 3 shows a curve illustrating the volt-ampere characteristic of the carrier frequency generator.

Fig. 4 shows input output curves for the detector rectifier. 60

Fig. 5 shows the form of signals produced by the modulating circuit of Fig. 1 and the corresponding received signals.

Fig. 6 shows the form of signals produced by the modulating circuit of Fig. 2 and the 65 corresponding received signals.

Fig. 7 shows diagrammatically transmitting and receiving channels of a multiplex high frequency carrier telephone system to which the multiplex audio frequency telegraph system of Fig. 1 may be applied. 70

Fig. 8 shows diagrammatically a multiplex radio telephone system to which the multiplex audio frequency carrier telegraph system of Fig. 1 may be applied. 75

Fig. 1 showing a multiplex carrier telegraph system employing carrier waves of audio frequency will first be described.

This system comprises a main line EL over which modulated carrier waves are to 80 be transmitted in one direction, a main line WL for transmission in the opposite direction, and a plurality of transmitting channels TL₁, TL₂, etc., and receiving channels RL₁, RL₂, etc., to connect a plurality of ordinary Morse telegraph equipments to the 85 main lines.

While only so much of the Morse telegraph equipment as is necessary for an understanding of the invention is shown, it 90 will be understood that Morse telegraph equipment such as shown in Fig. 55 of the article by Colpitts and Blackwell on "Carrier current telephony and telegraphy" in Transactions of American Institute of Electrical Engineers, vol. 40, 1921, may be associated with the transmitting and receiving channels. 95

The transmitting channels TL₁, TL₂ and TL₃ are coupled to the main line EL through 100 a transmitting terminal amplifier TTA common to all such channels at the same terminal.

The receiving channels RL₁, RL₂, and RL₃ are coupled to the main line WL through a 105 receiving terminal amplifier RTA common to all such channels at the same terminal.

While for purpose of illustration only two transmitting and two receiving channels are 110 fully shown, it will be understood that more

may be and, in practice, usually are provided.

The outgoing channels TL_1 , TL_2 and TL_3 are respectively supplied with carrier currents of different frequencies from the carrier frequency generators G_1 , G_2 and G_3 .

It will be understood, of course, that a separate generator or source of carrier current will be provided for each channel of the same system transmitting in the same direction. A multiple frequency rotating generator, such as disclosed in the copending application of Hugh M. Stoller Serial No. 644,071, filed June 8, 1923, or a harmonic oscillation generator may be employed.

Since separate main lines are employed for transmission in opposite directions, carrier currents of like frequencies may be employed for transmission over each line.

20 The carrier frequency generators G_1 , G_2 and G_3 may be common to a plurality of multiplex carrier systems like that shown in Fig. 1.

Thus these generators, as illustrated, also supply carrier currents to the transmitting channels of other multiplex audio frequency carrier telegraph systems, one of which is indicated by the transmitting channels TL'_1 , TE'_2 and TL'_3 .

30 In carrier transmission wherein a plurality of multiplex carrier signal systems are supplied with carrier currents from a plurality of generators or sources common thereto, two kinds of interchannel modulation originating at the transmitting terminal may occur as follows.

1. Modulation between channels of different systems operating with carrier currents of the same frequency.

40 2. Modulation between channels of the same system operating with carrier currents of different frequencies.

Means are provided to limit such interchannel modulation to such an amount that 45 the amplitude variations of the signals resulting therefrom do not cause any interference with the reception of signals.

The receiving channels are provided with means for increasing the current amplitude 50 discrimination of the receiving relays, so that the proper operation of such relays is not affected by the superposed interfering line currents of smaller amplitude including among others those interfering line currents 55 resulting from interchannel modulation.

All transmitting channels are similar, so a description of one will suffice.

The transmitting channel TL_1 includes a modulating circuit or modulator M_1 and a 60 transmitting band filter TBF_1 .

The modulating circuit M_1 comprises two impedance elements 1 and 2 included serially therein, an impedance element 3 in bridged relation to the circuit, and a trans-

mitting element or switch 4 having marking 65 and spacing contacts M and S for controlling the marking and spacing signals to be transmitted.

Impedance elements 1, 2 and 3 may take the form of non-inductive resistances. 70

The impedance of element 1 must be of such value that when the switch 4 is closed and opened to control the spacing and marking signals over its channel the impedance change in the modulating circuits of the 75 channels in other systems to which carrier currents of the same frequency are supplied from the same source, will not be sufficient to cause noticeable interfering modulation in such other channels. 80

More particularly, the adjusted value of the impedance of element 1 which limits the carrier current supplied to the input of the modulating circuit to a predetermined value, must be such that the summation of all carrier currents supplied from the same source to simultaneously operating channels does not exceed a value determined by the generator volt-ampere characteristic as will more fully hereinafter appear. 90

During a spacing signal, the element 3 is short circuited and the load on the generator is represented by the current through impedance 1. Impedance element 1 therefore serves to protect the generator against short 95 circuit.

During a marking signal, the short circuit is removed from element 3, and the load on the generator is represented by the current through impedance element 1 in series with element 3 shunted by element 2 in series with the surge impedance of band filter TBF_1 . 100

The generator voltage therefore varies while signals are being transmitted, the magnitude of such variations depending upon 105 the number of simultaneously operating channels and the relative values of impedance elements 1, 2 and 3 and the surge impedance of the band filter.

If the variation in voltage is large when 110 changing from marking to spacing signals or vice versa, the modulation between channels operating with carrier currents of the same frequency may be so great as to cause interference with the reception of the signals. 115 This interference takes the form of "cross-fire" or crosstalk which increases or decreases the amplitude of the signals and tends to break them up.

It is therefore important that this modulation between channels operating with the same carrier frequency be limited to such an amount as will not cause interference with the reception of signals. 120

Such modulation is the most when the 125 marking contacts of all the channels operating with the same carrier frequency are closed at the same time, since under such

conditions currents of the same frequency are being transmitted from these channels to the line.

It has been determined that, if, in such extreme case, the voltage variation does not exceed ten (10) percent of the open circuit terminal voltage of the generator, the modulation between channels operating with the same carrier frequency is not sufficient to cause interference with the reception of signals.

The impedance of element 1 therefore bears such a relation to the impedance of elements 2 and 3 and the surge impedance of the band filter TBF_1 , as viewed from the modulating circuit, that there is not more than a ten percent variation in generator voltage when changing from marking to spacing signals or vice versa.

20 Fig. 3 shows the volt-ampere characteristic of the generator with current output plotted as abscissæ against terminal voltage as ordinates.

When all channels, supplied with current 25 of the same frequency, are simultaneously transmitting spacing signals the current drawn from the generator is represented by I_s and the terminal voltage by V_s . When all such channels are transmitting marking 30 signals the current drawn from the generator is represented by I_m and the terminal voltage by V_m . V_o represents the open circuit terminal voltage of the generator.

Thus during the transmission of marking 35 and spacing signals by the channels operating with the same carrier frequency, the terminal voltage of the generator cannot vary more than $V_m - V_s$. Consequently the modulation between such channels is not sufficient 40 to cause interference with the reception of signals.

The combined impedance of elements 2 and 3 approximates the surge impedance of the transmitting band filter TBF_1 , as viewed 45 from the modulating circuit M_1 .

The value of the impedance of element 2 is dependent upon the frequency spacing of the channels of the multiplex carrier system.

The impedance of element 2 must be such 50 that, when the switch 4 is being operated to control the marking and spacing signals, the resulting change in impedance of the transmitting band filters of adjacent channels is not sufficient to interfere with the proper operation of such other channels.

The frequency spacing of the channels 55 may be great enough so that the value of the impedance of the element 2 may be reduced to zero, in which case the impedance of element 3 would approximate the surge impedance.

Ordinarily as the frequency spacing of the channels becomes closer, the value of the impedance of element 2 should increase.

60 The shunting effect of the band filter of

each transmitting channel upon the band filters of the adjacent transmitting channels on each side thereof with a given frequency spacing of channels and design of filters is determined by the impedance termination for the input of the filters.

When the impedance termination changes while signals are being transmitted, the energy absorbed from adjacent operating channels by the filter of an operating transmitting channel varies. This variation in energy absorption produces modulation between adjacent channels of the same system operating with carrier currents of different frequencies, thereby causing the amplitude of the signals to vary.

This signal amplitude variation, if of any considerable magnitude interferes with the reception of signals causing them to be 85 broken up.

It is important therefore that the variations in energy absorbed by each filter from the filters of adjacent channels be limited to such magnitude as will not interfere with the proper reception of the signals.

As previously stated the frequency spacing of the channels of the same system may be great enough so that impedance 2 may be reduced to zero, in which case the filter termination varies from zero to an impedance approximating the surge impedance of the filter while signals are being transmitted.

As the frequency spacing becomes closer, the change in impedance termination of the filters during the transmission of signals should become less. This may be accomplished by increasing the ratio of impedance 2 to impedance 3.

The switch 4 provided with a marking contact M and a spacing contact S is controlled by the sending relay 6 of the ordinary Morse telegraph equipment.

The sending relay 6 is controlled by a sending key 7.

When the sending key 7 is not being operated a switch 8 is closed to hold the relay 6 energized and thereby hold the spacing contact S open. When the sending key 7 is to be operated the switch 8 is opened by moving it to its dotted line position.

The transmitting band filter TBF_1 may be of the general type disclosed in U. S. patents to George A. Campbell Nos. 1,227,113 and 1,227,114 dated May 22, 1917. It is designed to pass only currents of the carrier frequency assigned to the transmitting channel TI_1 and currents of the frequencies within the upper and lower side bands and to suppress currents of all other frequencies.

The transmitting band filters in the other transmitting channels are similar to filter TBF_1 each being designed to pass only the carrier currents of the frequency assigned to

its channel and currents of the frequencies within the upper and lower side bands of such carrier frequency.

All receiving channels are similar so a description of one will suffice.

The receiving channel RL_1 includes a receiving band filter RBF_1 , an amplifier A_1 , and a rectifier R_1 .

The receiving band filter RBF_1 is similar to the transmitting band filter TBF_1 . It is designed to pass only carrier currents of the frequency assigned to the receiving channel RL_1 and currents of frequencies within the upper and lower side bands of such carrier frequency and to suppress currents of all other frequencies.

The amplifier A_1 inductively coupled to the receiving band filter RBF_1 may be of any well known type but as illustrated is a three element relay of the space current type.

The rectifier R_1 may be of any well known type, but as illustrated is a similar space current type relay.

The input current to the amplifier A_1 is regulated by a potentiometer 9.

The output circuit of the amplifier A_1 is inductively coupled to the input circuit of the rectifier R_1 through a transformer 10.

The rectifier R_1 controls the receiving relay 11 of the ordinary Morse telegraph equipment (not shown).

The relay 11 has three windings, one of which is included directly in the output circuit of rectifier R_1 . A second winding is inductively coupled with the rectifier output circuit through the transformer 12. This second winding commonly called the "kick winding" insures the quick response of the relay to received signaling currents. The third winding in series with a battery or other source of current is a biasing winding which biases the relay armature to one position.

When a certain value (for example 5 milliamperes) of signal current is delivered to the input circuit of the rectifier R_1 , the receiving relay 11 responds to a predetermined rectified current in the rectifier output circuit.

To prevent false operation of the receiving relay due to interfering line currents superposed upon the signal currents means are provided whereby amplitude discrimination is obtained and the relay is unaffected and is not responsive to such superposed interfering line currents.

The means for obtaining such amplitude discrimination comprises an impedance 13 which may take the form of a high resistance, included serially in the input or grid circuit of the rectifier R_1 .

To obtain a high degree of amplitude discrimination as indicated by the curves of Fig. 4 it has been found that the impedance

13 should be connected in the grid circuit between the battery 14 and the secondary winding of the input transformer 10.

In Fig. 4 input current from the line impressed upon the amplifier A_1 is plotted as abscissæ against rectified current from the rectifier R_1 as ordinates.

Curve A shows that when impedance 13 is not included in the grid circuit, small variations of input current cause correspondingly great changes in rectified current.

Therefore when the impedance 13 is not employed the superposed interfering line currents are reflected into the output circuit of the rectifier R_1 and cause the false operation of the receiving relay 11.

Curve B shows the rectified current variations for variations in input current when impedance 13 is connected between the secondary winding of the output transformer 10 and the grid of the rectifier R_1 .

According to this curve B for small changes in input current corresponding changes in the rectified current are comparatively great at or near the value of the rectified current (5 milliamperes) at which the receiving relay 11 operates, so the relay is affected by the superposed interfering line currents. Furthermore the efficiency of the receiving circuit is greatly decreased, for much greater input is required to obtain the proper value of rectified current for operating the receiving relay.

Curve C represents the variations in rectified current for amplifier input variations when impedance 13 is connected as shown in Fig. 1.

This curve shows clearly that at and near 5 milliamperes rectified current at which the receiving relay 11 operates changes in input current cause but relatively small changes in rectified currents. These small changes in rectified current do not affect the operation of the receiving relay.

The operation of the system of Fig. 1 is as follows assuming that signals originating in the Morse telegraph equipment associated with transmitting channel TL_1 are to be transmitted.

The operator after opening the switch 8 closes and opens the telegraph key 7 to form and transmit marking and spacing signals.

The closure of key 7 to initiate a marking signal causes the sending relay 6 to operate, thereby moving the transmitting element 4 from the spacing to the marking contact.

Opening of the spacing contact removes the short circuit from impedance element 3, thereby allowing currents of the frequency assigned to channel TL_1 to pass through band filter TBF_1 into the transmitting terminal amplifier TTA . The amplified current from the terminal amplifier is impressed upon the main line EL .

The duration of closure of key 7 determines whether the marking signal is a dot or a dash.

The opening of key 7 causes the sending relay 6 to release the transmitting element 4 which thereupon moves from its marking to its spacing contact.

When the transmitting element 4 engages the spacing contact S, impedance element 3 is short circuited thereby removing current of the frequency assigned to channel TL_1 from the band filter TRF_1 and consequently from the line EL .

A spacing signal is represented by the length of time between marking signals when current is removed from the line.

It will be observed that during a marking signal current is passing to line for a greater length of time than the duration of closure of the sending key 7. This difference is measured by the time of travel of the transmitting element 4 from the marking to the spacing contact. Therefore the marking signals are biased as will more fully appear.

The signals transmitted over the main line EL are received by the particular receiving channel at the distant terminal to which are assigned carrier currents of the frequency assigned to the transmitting channel TL_1 .

Inasmuch as the apparatus and circuits for only one terminal are shown, the operation of the system with respect to the reception of signals incoming over the main line WL will be described.

The marking signal currents incoming over the main line WL are impressed upon the receiving terminal amplifier RTA and the amplified currents therefrom are selected by the band filter in the proper receiving channel.

Assuming that the carrier currents of the operating transmitting channel at the distant station are of the frequency assigned to the receiving channel RL_1 , the incoming amplified signal currents from the receiving terminal amplifier are selected by the band filter TRF_1 .

The marking signal currents from the band filter TRF_1 pass through the potentiometer 9 and then after being amplified by the amplifier A_1 are impressed upon the input of the rectifier R_1 . The rectified currents cause the receiving relay 11 to operate and close its working contact 15 which controls the sounder or other receiving device in the Morse telegraph equipment associated with the receiving relay 11 of the receiving channel RL_1 .

Upon the cessation of the marking signal receiving relay 11 releases opening its working contact 15.

According to one way in which the invention may be practiced, a multiplex audio frequency carrier telegraph system having

ten channels operating in each direction over the respective main lines with a frequency spacing of 170 cycles between adjacent channels is provided with modulating circuits of the character illustrated in Fig. 1. When 70 the impedance elements of these modulating circuits are given the values set forth below and impedances 13 in the receiving circuits are given a value of two megohms the modulation between channels of different systems operating with carrier currents of the same frequency and between channels of the same system operating with carrier currents of different frequencies is not sufficient to cause interference with the proper reception 80 of signals.

Element.	Impedance.	85
1	2000 ohms.	
2	350 ohms.	
3	700 ohms.	

Fig. 2 shows a modulating circuit particularly adapted for systems operating at high speed. This modulating circuit may be substituted for the modulating circuits included within the dotted lines $a-a$ and $b-b$ of Fig. 1.

The modulating circuit of Fig. 2 has the elements thereof so organized as to form and transmit an unbiased marking signal.

The term "bias" refers to the duration of the received signal as compared to the duration of closure of the sending key, "light bias" meaning that the signal is of less duration than the closure of the sending key and "heavy bias" meaning that the received signal is of greater duration than the closure of the sending key.

Whether or not the signals are biased is not of so great importance when the system is being operated at low speed. However, when operating at high speed it is important that the signals be without bias as biased signals may interfere seriously with the proper reception thereof. As the speed of operation increases, the bias becomes relatively greater for the time of travel of the transmitting element 4 from the marking to the spacing contact does not change.

The formation and transmission of a marking signal by the modulating circuit of Fig. 1 actually begins when switch 4 disengages the spacing contact S and continues until this contact is again engaged by the switch.

It will be evident therefore, that, due to the time of travel of the switch 4 between the spacing and marking contacts, the duration of the transmitted and received marking signals is actually greater than the duration of closure of the sending key. This difference is measured by the time of travel of the switch 4 from the marking contact M to the spacing contact S.

As to the modulating circuit of Fig. 2, it

will be seen that while a marking signal is being formed and transmitted current is on the line from the time switch 4 disengages the spacing contact S until this contact is again engaged by the switch. However, while the switch 4 is traveling from the spacing to the marking contact and is returning from the marking to the spacing contact current of a predetermined amplitude passes to line. When the switch is in engagement with the marking contact current of greater amplitude passes to line. These different line current conditions are brought about by the peculiar organization of apparatus in the modulating circuit. Thus, while the switch 4 is moving from the spacing contact S to the marking contact M and likewise during its return movement the short circuits are removed from both impedance elements 2 and 3 so current of a predetermined amplitude passes to line. While the switch 4 is in engagement with the marking contact M impedance element 2 is short circuited so that current of greater amplitude passes to line.

When the modulating circuit of Fig. 2 is employed, the receiving relay 11 operates in response to the opening of the spacing contact and releases in response to opening of the marking contact.

Consequently, as will be more fully herein-after pointed out, the received marking signal is without bias and corresponds in duration to the length of time the sending key is closed.

When the impedance elements of the modulating circuit of Fig. 2 are given the values set forth below, the inter-channel modulation originating at the transmitting terminal is not sufficient to cause interference with the proper reception of signals.

Element.	Impedance.
1	2000 ohms.
2	700 ohms.
3	700 ohms.

It will be observed that due to the fact that elements 2 and 3 are of the same impedance the band filter has the same impedance termination while the transmitting element 4 is in engagement with either contact. While the element 4 is traveling between the contacts, the impedance termination of the filter is greater than during the time the element 4 is in engagement with either contact, whereby the amount of energy absorbed by the filter from adjacent channels is decreased and the amplitude of the signals being transmitted over such adjacent channels is increased. This inter-channel modulation, however, is not sufficient to interfere with the proper reception of signals.

In order that the character of the signals transmitted by the modulating circuits of

Figs. 1 and 2 may be better understood, reference is made to Figs. 5 and 6 showing curves which illustrate the condition of the signals from the time they are initiated by the sending key until they are received at the sounder or signaling device at the distant terminal.

Fig. 5 shows a series of curves illustrating the condition of the signals transmitted by the modulating circuit of Fig. 1.

The marking signals represented are dots (short curves) and dashes (long curves), the spaces therebetween representing the spacing signals.

The curves are in vertical alinement so as to afford ready comparisons.

The curves A indicate the duration of closure of the sending key 7 for the marking signals.

Curves B indicate the magnitude and duration of the direct current applied to the sending relay 6.

Curves C indicate the magnitude and duration of the carrier current passing to line during the time that the transmitting element or switch 4 is off its spacing contact.

It will be noted that carrier current is passing to line for a greater length of time than the sending key 7 is closed, the difference being represented by the time of travel of the switch 4 from the marking to the spacing contact.

Curves D indicate the magnitude and duration of the rectified current flowing through the operating winding of the receiving relay 11.

The duration of this current flow exceeds the duration of closure of the sending key 7.

Curves E represent the corresponding current flow in the kick winding of the receiving relay 11.

Curves F represent the combined current flow (curves D and E) through the operating and kick windings which is effective for operating the receiving relay.

The receiving relay operates when the magnitude of operating current is slightly greater than that represented by the dotted line f-f and releases when the magnitude of the operating current is slightly less than that represented by the same dotted line.

The receiving relay therefore remains in operated condition for a greater length of time than the length of time that the sending key 7 is closed.

Curves G represent the magnitude and duration of the signal current in the sounder or other signaling device controlled by the receiving relay armature and its contact 15.

Curves H represent the duration of the received signals at the sounder or other signaling device (not shown) controlled by the receiving relay 11.

Inspection of these curves shows that the transmitted and received marking signals

have a heavy bias and that the spacing signals have a light bias.

The biasing of the signals does not interfere with the proper reception of the signals in a system operated at low speed, but may become troublesome and cause interference with the proper reception of the signals if the system is operated at high speed.

Fig. 6 shows corresponding curves illustrating the condition of the signals when the modulating circuit of Fig. 2 is employed. These curves are designated by the same set of reference characters as employed in Fig. 5 so that comparisons may readily be made.

Referring to curve F of Fig. 6, the receiving relay operates when the magnitude of the operating current is slightly in excess 20 of that represented by the dotted line $f-f$ and releases when it is slightly less than that represented by the dotted line.

Inspection of these curves of Fig. 6 shows clearly that the received signals correspond 25 in duration to the length of closure of the sending key 7 and are therefore without bias.

If a receiving relay without a kick winding is used, curves E and F do not apply, 30 and the relay will operate when the rectified current increases to a magnitude represented by the dotted line $d-d$ and releases when the rectified current decreases to a magnitude represented by the dotted line 35 $d'-d'$.

Inspection of curves D shows that the marking signal (Fig. 5) transmitted by the modulating circuit of Fig. 1 is biased while that (Fig. 6) transmitted by the modulating 40 circuit of Fig. 2 although shifted along a time axis is unbiased.

Fig. 7 shows the terminal arrangement of a multiplex high frequency carrier system, to channels of which the multiplex audio 45 frequency carrier telegraph systems like those shown in Fig. 1 may be connected.

The terminal arrangement comprises a plurality of transmitting channels T_1L , T_2L , T_3L and T_4L and a plurality of corresponding receiving channels R_1L , R_2L , R_3L 50 and R_4L connected to a high frequency line ML .

This high frequency carrier system operates upon the group frequency basis, the 55 carrier currents for transmission in one direction being of frequencies within one group and those for transmission in the opposite direction being of frequencies within another group. All frequencies of one group are higher than those of the other group.

High pass and low pass directional filters HGF and LGF are provided for the purpose of separating currents of frequencies

within one group from those of frequencies 65 within the other group.

These filters may be of the general type disclosed in the Campbell patents, supra.

The filter HGF is designed to pass currents of all frequencies within the upper 70 group and to suppress currents of lower frequencies, while the filter LGF is designed to pass currents of frequencies within the lower group and to suppress currents of higher frequencies. 75

The main line ML may, of course, be utilized for the transmission of audio or other lower frequency currents, high and low pass filters being provided, as shown, to separate the lower audio and higher carrier frequency currents. 80

The multiplex audio frequency carrier telegraph system of Fig. 1 may be applied to a sending and a receiving channel of the high frequency carrier system (Fig. 7) by 85 connecting the secondary winding of the transmitting output transformer 16 and the primary winding of the receiving input transformer 17 (Fig. 1) to the respective terminals 18 and 19 (Fig. 7) of the transmitting and receiving channels T_1L and R_1L . 90

Since all of the high frequency transmitting and receiving channels are similar, only a portion thereof have been illustrated. 95

The high frequency channel T_1L includes a modulator $M-1$ and a transmitting band filter T_1BF .

The modulator $M-1$ may be of any well known type, such, for example, as the 100 vacuum tube modulator disclosed in Fig. 9 of the Colpitts and Blackwell article, supra.

A carrier source CS supplies high frequency carrier current to the modulator $M-1$. 105

The transmitting band filter T_1BF , of the general type disclosed in the Campbell patents, supra, is designed to pass currents of the carrier frequency assigned to its channel and currents of frequencies within either 110 the upper or lower side band of the carrier and to suppress currents of all other frequencies.

The high frequency channel R_1L includes a receiving band filter R_1BF , a demodulator 115 $DM-1$ and a low pass filter LPF_1 .

The receiving band filter R_1BF is similar to the transmitting band filter T_1BF . It is designed to pass currents of the carrier frequency assigned to its channel and currents 120 of frequencies within either the upper or lower side band of the carrier and to suppress currents of all other frequencies.

The demodulator $DM-1$ may be of any well known type, such as, for example, the 125 vacuum tube demodulator disclosed in Fig. 9 of the Colpitts and Blackwell article, supra,

The low pass filter LPF which may be of the type disclosed in the Campbell patents, supra, is designed to pass currents of the frequencies in accordance with which the high frequency carrier currents assigned to this channel are modulated and to suppress currents of higher frequencies.

The marking signals originating in the transmitting channel T_{1L} of the multiplex audio frequency carrier telegraph system and transmitted from the transmitting terminal amplifier TTA are impressed upon the modulator M-1. The currents comprising the marking signals so impressed upon the modulator M-1 modulate the high frequency carrier currents from the source CS. The modulated carrier currents are then transmitted to the band filter T_{1BF} which suppresses one of the side bands. The other side band and the carrier are transmitted through the high pass directional filter HGF to the high frequency line ML.

High frequency carrier currents modulated in accordance with the currents comprising the marking signals incoming from the line ML pass through the low pass directional filter LGF and are selected by the receiving band filter R_{1BF} . The modulated high frequency carrier currents transmitted through the band filter R_{1BF} are impressed upon the demodulator DM-1, where they react with the unmodulated high frequency carrier currents incoming from the line ML. Currents resulting from interaction of the received line currents are transmitted to the low pass filter LPF, which permits the passage of currents of the frequency in accordance with which the high frequency carrier currents were modulated but suppresses currents of higher frequencies. Such currents as pass through the low pass filter LPF₁ are transmitted through the receiving terminal amplifier RTA and are selected by the receiving band filter RBF_1 . These selected currents transmitted from the band filter RBF_1 are impressed upon the amplifier A₁. The amplified currents from amplifier A₁ are impressed upon the input circuit of the rectifier R₁. The resulting rectified signal currents operate the receiving relay 11, which closes its contact 15 thereby causing the operation of the usual sounder or other signal receiver of the Morse telegraph equipment.

Referring further to Fig. 7 it will be noted that the high frequency transmitting and receiving channels T_{2L} and R_{2L} couple a low frequency speech transmission line L to the high frequency main line ML.

These channels T_{2L} and R_{2L} are equipped with apparatus similar to that included in the channels T_{1L} and R_{1L} previously described.

The low frequency speech transmission

line L is associated with the high frequency transmitting and receiving channels T_{2L} and R_{2L} by means of a hybrid coil 20.

The two channels T_{2L} and R_{2L} are rendered substantially conjugate by the provision of an artificial line or net AL to balance the line L.

While only one transmitting and receiving channel of the high frequency carrier system is illustrated as having applied thereto a multiplex audio frequency carrier telegraph system like that shown in Fig. 1, it will be understood that one or more of the other high frequency channels may have such an audio frequency carrier telegraph system applied thereto.

Thus if it is desired to apply an audio frequency carrier telegraph system to the high frequency transmitting and receiving channels T_{2L} and R_{2L} this may be done by substituting such system for the apparatus shown to the left of the dotted line X-X of Fig. 7.

Fig. 8 shows the terminal arrangement of a multiplex radio telephone system, to the channels of which multiplex audio frequency carrier telegraph systems, such as shown in Fig. 1, may be connected.

The terminal arrangement comprises a plurality of transmitting channels TRL_1 , TRL_2 , TRL_3 and TRL_4 coupled to a transmitting antenna and a plurality of corresponding receiving channels RRL_1 , RRL_2 , RRL_3 and RRL_4 coupled to a receiving antenna.

The multiplex audio frequency carrier telegraph system of Fig. 1 may be applied to a transmitting and a receiving channel of the multiplex radio telephone system of Fig. 8 by connecting the secondary winding of the transmitting output transformer 16 and the primary winding of the receiving input transformer 17 (Fig. 1) to the respective terminals 21 and 22 (Fig. 8) of the transmitting and receiving channels TRL_1 and RRL_1 .

Since all of the radio transmitting and receiving channels are similar, only a portion thereof have been illustrated.

The radio transmitting channel TRL_1 includes an amplifier RA_1 , a modulator RM_1 and a transformer 23.

The amplifier RA_1 and the modulator RM_1 may be of any well known type, such as, for example, the vacuum tube amplifier and modulator disclosed in Fig. 9 of the Colpitts and Blackwell article, supra.

A carrier source RCS_1 supplies high frequency radio currents to the modulator RM_1 .

The circuits of the transformer 23 are tuned by means of the condensers 24 and 25 to the radio frequency assigned to the channel TRL_1 .

The transformers of the other transmit-

ting channels are similarly tuned to the respective carrier frequencies assigned thereto.

The radio receiving channel RRL_1 , includes a transformer 26 for coupling to the receiving antenna, a demodulator RDM_1 , and a low pass filter LPF.

The transformer 26 is a loosely coupled step-up transformer and is tuned by means of condensers 27 and 28 to the radio carrier frequency assigned to the receiving channel RRL_1 .

The demodulator RDM_1 may be of any well known type, such as, for example, the vacuum tube demodulator disclosed in Fig. 9 of the Colpitts-Blackwell article, supra.

The low pass filter LPF which may be of the general type disclosed in the Campbell patent, supra, is designed to pass currents of the frequencies in accordance with which the radio frequency currents assigned to this channel are modulated, and to suppress currents of higher frequencies.

The marking signal currents originating in the transmitting channel TL_1 , of the multiplex audio frequency carrier telegraph system are transmitted from the transmitting terminal amplifier TTA and impressed upon the modulator RM_1 . The currents so impressed upon the modulator modulate the radio frequency currents from the source RCS_1 . The modulated and unmodulated components of the radio frequency currents pass through the tuned antenna coupling and are transmitted from the transmitting antenna.

Modulated and unmodulated components of radio frequency waves incoming at the receiving antenna are selected by the tuned coupling in the receiving channel RRL_1 , and are then impressed upon the demodulator RDM_1 . These currents interact in the demodulator and the currents resulting from such interaction are transmitted to the low pass filter LPF which permits the passage of currents of the frequency in accordance with which the radio frequency currents were modulated and suppresses currents of higher frequencies. Such currents as pass through the low pass filter LPF are transmitted through the receiving terminal amplifier RTA and are selected by the receiving band filter RBF_1 . These selected currents transmitted from the band filter RBF_1 are impressed upon amplifier A_1 . The amplified currents from the amplifier A_1 are then impressed upon the input circuit of the rectifier R_1 . The resulting rectified signal currents operate the receiving relay 11, which closes its contact 15, thereby causing the operation of the usual sounder or other signal receiver of the Morse telegraph equipment associated with the receiving relay.

Referring further to Fig. 8, it will be

noted that the radio transmitting and receiving channels TRL_2 and RRL_2 , couple a low frequency speech transmission line L to the transmitting and the receiving antennæ. These channels TRL_2 and RRL_2 , are equipped with apparatus similar to that included in the channels TRL_1 and RRL_1 , previously described.

The low frequency speech transmission line L is associated with the radio transmitting and receiving channels by means of a hybrid coil 29, and the two channels are rendered substantially conjugate by the provision of an artificial line or net AL to balance the line L .

While only one transmitting and receiving channel of the radio system is illustrated as having applied thereto a multiplex audio frequency carrier telegraph system like that shown in Fig. 1, it will be understood that one or more of the other transmitting and receiving radio channels may have such an audio frequency carrier telegraph system applied thereto. Thus, if it is desired to apply the audio frequency carrier telegraph system to the radio transmitting and receiving channel TRL_2 and RRL_2 , this may be done by substituting such system for the apparatus shown to the left of the dotted line $Y-Y$ of Fig. 8.

The invention set forth herein is, of course, susceptible of various other embodiments and adaptations.

The invention claimed is:

1. In carrier transmission, a plurality of transmission lines each having a carrier channel superposed thereon, a source of carrier current, means for supplying carrier current of the same frequency from said source to a carrier channel of each line, a series resistance element and a shunt resistance element in each channel, and means in each channel located between the line and the series and shunt resistances for controlling the amount of carrier current from said source supplied to the line to transmit signals, whereby the transmission of disturbing variations between the channels of the different lines due to impedance changes therein during signaling is prevented.

2. In carrier transmission, a source of carrier currents, a plurality of transmission lines each having a carrier channel superposed thereon, means for supplying carrier current of the same frequency from said source to a carrier channel of each line, a shunt resistance element and a series resistance element in each of said channels, a signal transmitting element in each channel located between the line and said shunt and series resistance elements, said signal transmitting element being adapted to intermittently short-circuit said shunt resistance element to vary the amount of carrier current supplied to the line to transmit sig-

- nals, whereby variations in the amount of carrier current continuously drawn from said source during signaling operations is maintained within predetermined limits.
6. 3. In carrier transmission, a plurality of transmission lines each having a carrier channel superposed thereon, a source of carrier currents, means for supplying carrier current of the same frequency from said 10 source to a channel of each of said lines, series and shunt resistance elements in each channel, and means in each channel adapted to be connected in shunt thereto between certain of said resistance elements for intermittently varying the amount of carrier current applied to the line to transmit signals.
4. In carrier transmission, a plurality of transmission lines each having carrier channels superposed thereon, a common source 20 supplying carrier current of the same frequency to a channel of each of said lines, a shunt resistance element and a plurality of series resistance elements in each of said channels supplied from said source, a signal transmitting element in each channel adapted to intermittently short-circuit the shunt resistance element to control the amount of carrier current from said source supplied to 30 the line to transmit signals, one of said series resistances in each channel being located between the signal transmitting element and the line, said one of said series resistances being of such value as to prevent during the 35 operation of the signaling element in the channel such impedance changes as would cause disturbing variations to be transmitted between adjacent channels of the same line.
5. In carrier transmission wherein a plurality of transmitting channels of different carrier signaling systems are supplied with carrier currents of the same frequency from the same source; a band filter in each channel; and a modulator for each channel comprising impedances in series and bridged relation thereto, and means to intermittently change the electrical relation of one of said elements to the channel to control the signals transmitted, said impedances and the 50 input surge impedance of the filter being so related that during the transmission of signals the voltage variations of the input carrier currents to the channels are within predetermined limits.
55. 6. In carrier transmission wherein a plurality of transmitting channels of different carrier signaling systems are supplied with carrier currents of the same frequency from the same source; a band filter for each channel; and a modulator for each channel comprising impedances in series and bridged relation thereto, and means to intermittently short circuit the bridged impedance to control the signals transmitted, said impedances 60 and the input surge impedance of the filter being so related that during the transmission of signals the voltage variations of the input carrier currents to the channels are within predetermined limits.
7. In a signaling system, the combination 70 of a rectifier having an input and an output circuit, an input transformer connecting to the input circuit an incoming circuit over which signaling currents are transmitted, a signal receiver in the output circuit, and amplitude discriminating means including an impedance connected to said input circuit to reduce the effect of incoming interfering line currents superposed on the signal currents on the operation of the signal receiver with 75 respect to the effect of said signal currents on the operation of said receiver.
8. In a signaling system, the combination 80 of a rectifier having input and output circuits, means to couple the input circuit to an incoming transmission channel, a signal receiver in the output circuit, a source of current in the input circuit, and a high impedance element in the input circuit positioned between and in series with the current source and the coupling means in said input circuit whereby the signal receiver is unaffected by incoming interfering channel currents.
9. In a signaling system, the combination 85 of a rectifier having input and output circuits, means to couple the input circuit to an incoming transmission channel, a signal receiver in the output circuit, a source of current in the input circuit, and a high resistance element positioned between and in 90 series with the current source and the coupling means in said input circuit whereby the signal receiver is unaffected by incoming interfering channel currents.
10. In a multiplex carrier transmission 95 system, the combination of a plurality of transmitting channels supplied with carrier currents of different frequencies; a main channel coupled to the transmitting channels; 110 a band filter for each transmitting channel; and a modulator for each transmitting channel comprising impedances in bridged and series relation to the channel and forming an input impedance termination for the 115 filter thereof, and a transmitting element to change the electrical relation of one of said impedances to the channel to control the signals transmitted, said impedance and input surge impedance of the associated band filter being so related that during the transmission of signals the modulation between adjacent channels for a given frequency spacing is limited to a predetermined amount.
11. In a multiplex carrier transmission 120 system, the combination of a plurality of transmitting channels supplied with carrier currents of different frequencies; a main channel coupled to the transmitting chan- 125

- nels; a band filter for each transmitting channel; and a modulator for each transmitting channel comprising impedances in bridged and series relation to the channel and forming an input impedance termination for the filter thereof, and a transmitting element to short circuit the bridged impedance to control the signals transmitted, said impedances and the input surge impedance of the associated band filter being so related that during the transmission of signals the modulation between adjacent channels for a given frequency spacing is limited to a predetermined amount.
12. A multiplex carrier telegraph system comprising a plurality of transmitting channels coupled to a transmission line, means to supply to the respective channels carrier currents of different frequencies, a band filter in each channel, modulating means for each channel including a switch to intermittently short circuit the channel to provide marking and spacing signals, an impedance element to prevent short circuiting the source of carrier current when the channel is short circuited, and bridged and series elements whose combined impedance approximates the input surge impedance of the band filter of the channel, the impedance of the series element being determined by the frequency spacing of the channels.
13. In a carrier signaling system, a transmitting member movable between two contacts to control the application and withdrawal of carrier current to and from a transmission line, and a receiving relay associated with the line and having a working contact actuated in response to said carrier current to close only in response to the line current condition produced by engagement of said member with one of its two contacts and to open only in response to the line current condition produced by engagement of said member with its other contact.
14. A carrier signaling system having in combination a source of carrier oscillations, a transmitting channel supplied thereby, and means to modulate the carrier oscillations to form marking and spacing signals, said modulating means including a switch movable between two contacts connected with the transmitting channel and an impedance element therein and adapted during the movement of the switch from one contact to the other and back to form a marking signal beginning and ending with carrier oscillations of a predetermined amplitude with the intermediate portion of the signal of greater amplitude.
15. A carrier signaling system having in combination a source of carrier oscillations, a transmitting channel connected thereto, a transmission line coupled to the transmitting channel, and means to modulate the carrier oscillations to form marking and spacing signals, said modulating means including a switch movable between two contacts so connected with two impedance elements that during the movement of the switch from one contact to the other and back again it forms a marking signal beginning and ending with carrier oscillations of a predetermined amplitude with the intermediate portion of greater amplitude.
16. A carrier telegraph system comprising a transmitting channel, a source of carrier oscillations connected thereto, and means to modulate the carrier oscillations, said means including a switch to intermittently open and close a circuit of low impedance bridged across the channel to provide marking and spacing signals and an impedance element under control of the switch included in series with the channel when the low impedance circuit is closed and removed electrically from the channel when the low impedance circuit is opened.
17. A carrier telegraph system comprising a transmitting channel, a source of carrier oscillations therefor, means to modulate the carrier oscillations supplied to the channel to form marking and spacing signals, said modulating means including a switch having associated spacing and marking contacts, an impedance element in bridged relation to the channel and an impedance element in series relation to the channel, and means so associating the switch and contacts with the impedance elements that when the switch engages the marking contact the bridged element is in circuit and the series element is in effect removed from circuit, when the switch is traveling between the contacts both elements are in circuit, and when the switch engages the spacing contact the series element is in circuit and the bridged element is in effect removed from circuit.
- In witness whereof, I hereunto subscribe my name this 29th day of March, A. D. 1923.
- MAURICE B. LONG,
